AIRCRAFT FURNITURE

Hubert S. Dale, Middle River, Md., assignor to The
Glenn L. Martin Company, Baltimore, Md.

Application June 24, 1937, Serial No. 150,054

3 Claims. (Cl. 155—170)

This invention relates to aircraft furniture and more particularly, but not necessarily, to an aircraft chair of the reclining type.

It is one object of this invention to provide 5 an improved aircraft chair having a novel retractable leg and foot rest.

Another object is to provide in combination 10 with a conventional chair having an adjustable or reclining back, an adjustable seat, an improved leg and foot rest that shall be easily and readily moved to and from a stowed position located within the confines of the chair.

A further object is to provide an improved leg 15 and foot rest in combination with a chair, which leg and foot rest may be folded into a compact arrangement and stowed within the confines of the said chair.

A still further object is to provide a chair 20 having the above combined characteristics that shall contain novel means for retracting the leg and foot rest within the confines of the chair.

An additional object is to provide an improved leg and foot rest in combination with a chair, 25 which leg and foot rest requires no latches in the open position.

Another object is to provide in combination 30 with a chair an improved leg and foot rest which leg and foot rest supports the weight of the legs of an occupant near the calf and at the heel.

The above and other objects will be made apparent throughout the further description of the invention when taken in connection with the accompanying drawings, wherein like reference characters refer to like parts. It will be understood 35 that the drawings are not a definition of the invention but merely illustrate forms by means of which the invention may be effectuated. The invention will be defined by the appended claims.

40 In the drawings:

Figure 1 is a perspective view of two aircraft chairs of the reclining type illustrating one embodiment of the invention, one chair showing a leg and foot rest placed in a folded position beneath the chair and the other chair showing the leg and foot rest in position for use.

Fig. 1A is a cross-sectional view showing the attachment of a trackway to a bracket.

Figure 2 is a side view of a track together with 50 a leg and foot rest in the open position.

Fig. 2A is a plan view of a detail in Fig. 1.

Figure 3 is a fragmentary view of a chair rod embodying a part of the invention.

Fig. 4A is a plan view of a detail in Fig. 4.

Figure 4 is a side view of a track together with 55

a leg and foot rest in the open position and embodying another form of the invention.

Figure 5 is a perspective view of the embodiment of Fig. 4.

Referring to the drawings, the forms shown in Figures 1 to 3, inclusive, illustrate one embodiment of the invention, in which 1 indicates an aircraft chair of the reclining type in its entirety having a conventional means 34 for the purpose of reclining the back 39 of said chair, 10 a suitable means 35 for the purpose of adjusting the seat 2 of said chair, a leg and foot rest attached to said chair, a hollow tube frame 3 supporting the said seat, the said hollow tube frame running under and parallel to the edges 15 of said seat, the said hollow tube frame being attached by suitable means to each leg panel 9 and 9a which support said hollow tube frame 3.

On the front bar of hollow tube frame 3 and, 20 near each end thereof and welded thereto, spaced plates 11 and 11a are suspended at a rearward sloping angle, each of said plates having an opening 23, the purpose of which will be understood as the description of the invention progresses.

A pair of arcuate shaped tracks 4 and 4a, 25 each possessing a longitudinally running slot 27, are attached by suitable means as by welding as shown in Fig. 1A to plates 11 and 11a, respectively, and said tracks run substantially parallel to each other and to leg panels 9 and 9a of 30 aircraft chair 1 to a point under the rear edge of seat 2, each of the said tracks being held in position by a supporting bar 7 attached to each track by means of a side bracket 6. Supporting bar 7 extends upward at a slightly sloping angle 35 and is attached at its other end by means 8 to tube frame 3. Supporting bar 7 serves in addition to hold the track to which it is attached sufficiently above the floor to allow leg and foot rest 10 to slide freely under the track. Brace 40 15 attached to the end of each track by means of a bolt 13 serves to hold said tracks in relative position to each other and in addition acts as a stop for roller 16.

Leg and foot rest 10 is composed of two sections, leg section 17 and foot section 11a connected by means of a hinge 18 in such manner that foot section 11a can be folded under leg section 17 as shown in aircraft chair 1a of Figure 1. Foot section 11a is attached to leg section 17 at an angle, the upper surfaces of said sections in operative position forming in effect a curve for the purpose of supporting the weight of the legs of an occupant of the chair near the calf and at the heel. A pair of short legs 19 45 50 55

and 19a, attached one at each side of the trailing edge of foot section 17a, extend downwardly to a point of contact with the floor when the leg and foot rest is in position for use, said legs serving to support the weight of foot section 17a. The said foot section is provided with an upholstered cushion 20 covering its upper half and fastened thereto by conventional means, while the lower half of said foot section is smoothly covered with suitable material. Leg section 17 has an upholstered cushion 20a similar to that provided for the foot section, the said cushion covering the entire surface of leg section 17. The two cushions are placed at such angle that they support the legs of an occupant of the chair in a comfortable manner. Base 21 of leg section 17 extends rearward and by means of a pair of curved arms 22 and 22a to points inside openings 23 of plates 11, each of said curved arms having at these points a roller 16 attached in such manner that the shaft of roller 16 rests in a pocket formed by U-shaped slot 23 in plate 11, which is the terminal of track 4. When leg and foot rest is not in use, foot section 17a is folded under leg section 17, the folded leg and foot rest is then pushed back, roller 16 leaves pocket of track 4 and permits said folded leg and foot rest to slide under the seat to a stop provided by brace 15, at which point upholstered cushion 20 of foot section 17a rests on the floor. Dotted section of Figure 1 shows folded leg and foot rest partially pushed under chair 1.

Figure 4 indicates another form of the invention in which aircraft chair 1, partially shown in side view, has a folding leg and foot rest 10 slidably connected by roller 16 to a pair of arcuate shaped tracks 4. In this form track 4 having slot 27 is suspended rearward from each end of the front bar of the hollow tube frame 3, said track being curved at an angle allowing its opposite end to rest on the floor, in such manner that the rear of the folded leg and foot rest 10 is suspended from said track. This form of the invention eliminates supporting bar 7 shown in Figure 2. At their lower ends the tracks are connected to each other by means of a round brace 26, the said brace serving for the purpose of maintaining the said tracks in fixed relation to each other, brace 26 acting at the same time as a stop for rollers 16.

Leg and foot rest 10 is shown in the extended position in Figure 4 in which foot section 17a of the said leg and foot rest is covered on its surface with a mat 30 of suitable material. Foot section 17a possesses an adjustable upturned bracket 29, slidably attached to the said foot section and extending along part of the lower side edges of foot section 17a to form a bar against which the feet may be placed. For the purpose of adjusting bracket 29 to the length of the leg of a person occupying the aircraft chair, an S-shaped latch 36 is attached to the said bracket in such manner that the turned down end of said latch engages notches 38, the latter being placed on the sides of the foot section at spaced intervals. Leaf spring 37 is mounted inside bracket 29 in such manner that said spring holds latch 36 in position while the latter engages a notch 38. Foot section 17a extends in a downward sloping line from leg section 17, to a point above the floor, the said leg and foot sections being supported at their juncture by leg 28 attached at 32 to the hinged edge of foot section 17a. Leg 28 is preferably a solid panel extending completely across foot section 17a and is attached to said foot section at

an angle to permit said leg to rest on the floor when the two sections are in the open position, rolling bar 31 being attached to the lower edge of said leg. Foot section 17a together with attached leg 28 is hingedly connected to leg section 17. When the leg and foot rest is in the stowed position, foot section 17a together with attached leg 28 is folded over leg section 17 in such manner that leg 28 is raised to a substantially upright position shown in the dotted section of Figure 4. At the same time bracket 29 of foot section 17a rests in a slot 33 in leg section 17. Round brace 26 at the terminal of each track resting on the floor serves as stop for folded leg and foot rest, the rear end of said leg and foot rest being positioned in recesses formed in the pair of tracks, in such manner that the upturned leg 28 forms a shield extending from the folding edges of the leg and foot rest 10 to a point near the forward edge of the seat of the aircraft chair, greatly eliminating draft.

While I have illustrated and described two embodiments of the invention, it will be apparent to those skilled in the art that the present invention may be equally applied to chairs, wherein similar conditions exist, and that it is expected that certain modifications, changes, alterations, substitutions, additions and omissions may be made in the construction here illustrated without departing from the spirit and scope of the appended claims.

I claim:

1. An aircraft chair having a foldable leg and foot rest, an adjustable bracket attached to the foot section of said leg and foot rest, means for adjusting the said bracket, said means including a spring controlled latch mounted on said bracket and engaging locking means on said foot rest section, said foot section being foldably connected to said leg section, and a slot in the leg section of said leg and foot rest for the reception of the said bracket together with adjusting means of the said bracket.

2. In combination with a seat, means for supporting said seat above a floor, a collapsible leg and foot rest mechanism comprising a leg rest section, means for supporting one end of said leg section at a point adjacent the front edge of said seat, means for guiding said end from said point to a rearward position beneath said seat and adjacent said floor, a foot rest section foldably hinged to the other end of said leg section, the hinged ends of said leg and foot sections being adapted and arranged to be supported by said floor when said one end of said leg section is in rearward position beneath said seat, and panel means rigidly secured to said foot section for supporting said foot section in operable position above said floor, said panel means being adapted and arranged to form a draft barrier beneath said front edge of said seat when said foot section is folded and in rearward position.

3. A chair having a supporting frame and a seat, trackways secured to said frame adjacent the front edge of said seat and being curved downwardly and rearwardly to rest upon the floor beneath said seat, a leg rest section slidably fastened at one end to said trackways, a foot rest section hingedly attached at one end to said leg section, a panel rigidly attached to the hinged end of said foot section to extend upwardly when said foot section is folded upwardly over said leg section and said leg section is drawn inwardly and downwardly beneath said seat.

HUBERT S. DALE. 75
